OIL BURNING HEATER

Leo L. Williams, Cleveland Heights, Ohio

Application January 5, 1935, Serial No. 558

12 Claims. (Cl. 158—94)

This invention relates to oil-burning devices and, as one of its objects, aims to provide a burner which will operate efficiently on kerosene oil, or other suitable liquid fuel, and which is adapted to be embodied in a heater of such form and attractive appearance as to render the latter adaptable to household and other uses.

Another object of the invention is to provide an improved liquid-fuel burning device which is capable of rendering more efficient and satisfactory service by reason of its having a laterally elongated housing, and novel burner mechanism in the housing including a correspondingly elongated wick.

15 A further object of the invention is to provide an improved oil-burning device, of the type referred to, which is capable of rendering more efficient and satisfactory service by reason of its having a laterally elongated housing with air directing means arranged therein to provide an air passage elongated in the direction of elongation of the housing, and wherein the liquid-fuel burning means includes an elongated wick disposed in or adjacent to the air passage.

25 It is also an object of this invention to provide improved liquid fuel burning means having a wick and an air distributor in cooperating relation to the wick, and wherein novel supporting and adjusting means is provided for the wick and distributor.

30 Yet another object of the invention is to provide a liquid-fuel burning device having a wick and an air supply means, and wherein novel means is provided for adjusting the wick and correspondingly controlling the air supply.

35 The invention may be further briefly summarized as consisting in certain novel combinations and arrangements of parts, hereinafter more fully described and particularly set out in the appended claims.

In the accompanying sheets of drawings,

Fig. 1 is a vertical transverse section taken through a heater having my novel liquid-fuel burning means embodied therein.

45 Fig. 2 is a partial sectional plan view of the burner, taken as indicated by line 2—2 of Fig. 1.

Fig. 3 is a partial vertical longitudinal section taken as indicated by line 3—3 of Fig. 1.

50 Fig. 4 is a partial transverse sectional view, on a larger scale, taken through the air distributor and the adjusting means as indicated by line 4—4 of Fig. 2.

Fig. 5 is a partial transverse sectional view taken on line 5—5 of Fig. 4.

55 Fig. 6 is a partial sectional view taken at an

end of the housing as indicated by line 6—6 of Fig. 1.

Fig. 7 is an elevational view showing a portion of the wick and illustrating the construction thereof.

5 In the accompanying drawings to which detailed reference will now be made, I have shown what I now regard to be a preferred embodiment of the liquid-fuel burning device of my invention. It will be understood, of course, that the invention 10 may be embodied in various other constructions and arrangements within the scope of the appended claims.

As shown in the drawings, the improved liquid-fuel burning device of my invention comprises, 15 in general, a housing 10, and liquid-fuel burning apparatus 11 arranged in the housing. As will be explained more fully hereinafter, the construction and arrangement of the housing and the fuel burning means are such that heat is efficiently 20 and economically produced by the combustion of kerosene oil, or other suitable liquid fuel. The housing for the device may be constructed to present a very attractive appearance, and to render the device suitable for use in fireplaces or 25 elsewhere in homes and for various other kinds of service.

The housing 10 is preferably of sheet metal construction and, as shown in the drawings, both the housing and fuel burning means are laterally 30 elongated. The housing is provided with end walls 13 and 14, and with front and rear walls 15 and 16 extending between the end walls. The housing is preferably open at the bottom thereof for the free admission of air into the lower 35 chamber 17 in which the fuel tank 18 is disposed. The fuel tank may be supported in the chamber 17 by providing the ends of the housing with angle member supports 19, or the like, upon which end portions of the tank rest and are slidably 40 supported. Air will have free access to the chamber 17 through the open spaces 20 and 21 which are located, respectively, at the front and rear of the tank 18 when the latter is in place. If desired, rows of openings 22 and 23 may also be provided 45 in the front and rear walls 15 and 16 for the admission of air to the chamber 17.

The housing also has a top wall 24 which may, if desired, be formed as an integral continuation of the front and rear walls 15 and 16. The top 50 wall is preferably shorter, in the direction from front to back, than the corresponding dimension of the bottom of the housing so that the front and rear walls may be inclined toward each other. The purpose of such inclination will be later ex- 55

plained. As seen in Fig. 2, the housing also has what may be conveniently termed an upper chamber 25, and provision is made for the discharge of heated air and gases from this chamber. Rows 5 of discharge openings 26 and 27 may be formed, respectively, in the front and rear walls for this purpose. The top wall 24 may also be provided with discharge openings 28 which may be controlled by a movable damper 29.

10 Without describing the housing structure further at this time I wish to direct attention to the liquid-fuel burning means 11. As best shown in Figs. 2 and 3 of the drawings, the liquid-fuel burning means includes the tank 18, which may 15 be of rectangular or other form, but which is preferably elongated correspondingly to the housing such that its ends may have sealing engagement with the end wall structure of the housing. The tank may be of sheet metal, or other suitable 20 construction, and is preferably of such width that the body of oil therein will have an extensive surface area. This is desirable because changes in the oil level will be relatively small for changes in the state of charge of the tank, and hence 25 will minimize the extent of variation in the capillary action of the wick. The top wall 31 of the tank is preferably, though not necessarily, sloped in opposite directions, as indicated in Fig. 2, and is provided with an elongated opening in which is 30 fitted a correspondingly elongated bushing or reinforcing flange 32. This bushing is preferably constructed with a recess 33 therein, having sloping side walls, as indicated in Fig. 2, and with an opening 34 which connects the recess of the 35 bushing with the interior of the tank.

The liquid-fuel burning means also includes a burner mechanism comprising an elongated closure member 35 for the opening of the bushing 32, an elongated or relatively wide flat wick 36 40 extending through the closure member, and an elongated hollow air diffuser or flame spreader 37 in cooperating relation with the wick. The elongated closure member 35 may be of any suitable construction and is here shown as being formed 45 of sheet metal and as having a flat or laterally elongated vertical wick tube 39 through which the wick 36 extends. The closure member may be constructed with a laterally elongated enlargement or chamber 49 which houses a part of the 50 wick adjusting mechanism. The ends of the closure structure may be formed by upright rigid members 40', constructed of cast metal or other suitable material, and to which the sheet metal portions of the closure structure may be connected as shown in Fig. 5.

The closure member 35 may be constructed with folded or doubled portions 41 and 42 forming flanges which extend, respectively, along the base of the wick tube and along the rear edge of the 60 enlargement 40. The closure member may also have integral angular flange portions 43 which extend downwardly and inwardly from the flanges 41 and 42. When the closure member is in position to close the opening to the tank, as shown 65 in Fig. 4, the flanges 41 and 42 seat against the top of the bushing 32 and the flanges 43 extend into the bushing recess and engage the sloping sides thereof.

The laterally elongated wick 36 extends upwardly through the wick tube 39, and is of such proportions that the upper edge 45 thereof may project from the wick tube while the lower portion 46 thereof extends downwardly through the opening 34 and into the tank 18.

70 75 If desired, the closure member 35 may be hinged

to the tank, preferably to the bushing 32, by spaced hinges 47 having the leaves thereof connected respectively to the bushing and to the folded metal forming the flange 41. The hinge connection permits the closure member to be 5 swung relative to the bushing 32 thereby uncovering the opening 34 into the tank and affording access to the lower portion of the wick. The hinge mounting for the closure member permits the latter to be swung to the open position for the insertion of a new wick into the wick tube, or for any other purpose for which it may be desirable to have access to the tank opening. The closure member 35 may be retained in its closed position by suitable locking means such as the spring 10 latches 48 which cooperate with the flange 42.

As mentioned above, the liquid-fuel burning mechanism also includes a laterally elongated hollow air distributor or flame spreader 37 which is arranged in adjacent relation to the upper end 20 of the wick tube and in cooperating relation with the wick. The air distributor is preferably of sheet metal construction and may comprise outer and inner members 49 and 50 of irregular shape, which when assembled as shown in Figs. 1 and 25 4 of the drawings, provide an elongated air chamber 51. The outer member 49 may be shaped to form the top, back and bottom walls of the chamber 51, and the member 50 may be arranged to form the front wall of this chamber. Those portions, of the member 49, which form the top and back walls 52 and 53 of the distributor chamber are imperforate and prevent the direct passage of air upwardly in back of the wick. That portion, of the member 49, which forms the bottom 30 wall of the chamber 51 of the distributor, is provided with one or more relatively large openings 55 which admit air to this chamber from the housing chamber 17.

The distributor may be provided with a projecting part or flange 56 which projects generally forwardly adjacent the upper end of the wick tube and which may be formed as an integral extension of one edge of the member 49. The projecting part 56 may be formed with an upwardly and 45 forwardly inclined section 57 which is spaced to the rear of the wick tube to form the air passage 58, and with a laterally forwardly extending section 59. The section 57 is provided with relatively large perforations 60, but the section 59 is 50 imperforate and the under side thereof is engaged by the top edge 45 of the wick.

The member 50 which forms the front wall of the distributor may have the upper portion thereof bent to substantially Z-shape, and may have a 55 doubled portion forming a flange or rib 61 extending forwardly just above the flange section 57 with a passage 62 therebetween. Numerous relatively small perforations 63 are formed in the front wall above the rib 61, and similar perforations 64 are 60 formed through this wall below the rib to connect the chamber 51 of the distributor with the passage 62.

The purpose of the distributor or flame spreader 37 is to regulate and distribute the air for 65 combustion and to control the flame so that the fuel will be burned efficiently with substantially no burning of the wick. It will be seen from Figs. 1 and 4 that the projecting part 56 of the distributor covers and shields the back and top 70 edge of the wick, and that only the front face of that portion of wick, which extends above the wick tube, is exposed. This arrangement prevents burning of the fuel from the rear face and top edge of the wick and permits burning of the 75

fuel only from the front face of the wick. When the fuel is burned from one face only of the wick, such as the front face in this instance, I find that burning of the wick itself is reduced to a minimum.

In the operation of the burner, air flows upwardly from the lower housing chamber 17 and through the large openings 55 into the chamber 51 of the distributor. From this chamber the air flows forwardly through the perforations 63 of the front wall to the area in which the burning of the fuel is to occur. Some of the air also flows forwardly through the perforations 64 and in so doing induces a flow of air upwardly through the passage 58 behind the wick and through the relatively large perforations 60. The air flow through the passage 58 picks up fuel vapor from the rear face of the wick and carries such vapor out through the passage 62 into the burning area. The tendency for fuel to accumulate at the back of the wick and to seep therefrom is thus greatly lessened.

The burner mechanism may include a vertical screen-like member 65 which is mounted on the closure member 35 and extends upwardly in front of the wick tube 39 with an air passage 66 therebetween. During the operation of the burner, air from the housing chamber 17 also flows through the openings of the screen 65 and upwardly through the passage 66 in front of the wick tube. Some of this air may be used for combustion purposes and the remainder is heated by the flame and serves as a heat conveying medium to be discharged from the heater.

Reverting now to the construction of the housing 10, I provide means for directing the air, which is admitted to the housing chamber 17, toward the wick and the distributor 37. This air directing means may comprise transverse sheet metal partition members 70 and 71, which are connected respectively to the front and rear walls 15 and 16, and which separate the lower and upper housing chambers 17 and 25. These partition members are disposed above the fuel tank 18, and are preferably arranged with inner edge portions thereof spaced apart to provide a slot-like opening or passage 72 which is elongated and extends for substantially the full length of the interior of the housing and in or adjacent which the wick tube and distributor 37 are disposed.

As shown in Figs. 1 and 4 of the drawings, the partition member 70 may be provided at the inner edge thereof with a depending flange 73, and the partition member 71 may be provided at its inner edge with an upwardly extending part or wall 74. The space between the flange 73 and the wall 74 forms the air passage 72 which connects the lower chamber of the housing with the upper chamber thereof.

The tank 18 is so located in the lower part of the housing that the wick tube 39 and air distributor 37 will extend into the air passage 72 with portions of imperforate rear wall 53 of the distributor engaging the wall 74 of the partition member 71. With the tank in this position the depending flange 73 of the partition member 70 also engages the upper edge of the perforated screen member 65.

If desired, cooperating means may be provided on the housing and tank for positioning the latter so that the wick tube and air distributor will be correctly disposed in the air passage 72. Such cooperating means is shown in this instance as comprising locating lugs 75 on the angle members 19 and one or more retaining latches 76.

The lugs 75 may be struck up from the angle members 19 for engagement with the rear edge of the tank, and the latches 76 may be pivoted on the front of the tank near the ends thereof for engagement in recesses of the angle members. 5 When the tank is in the position shown in Fig. 1 with the parts of the burner mechanism in cooperating relation with the partition members, as just explained above, it will be seen that the air which enters the bottom of the housing cannot 10 flow upwardly therein except through the passage 72 and in close proximity to the wick with some of the air flowing through the distributor 37.

The tank 18, with the burner mechanism thereon, is preferably removable from the housing and, to facilitate such removal, I may construct the front wall 15 of the housing with a hinged lower section 78. The partition member 70 is preferably connected to the hinged section 78 so that 20 when this section is swung outwardly to open the housing, the flange 73 of the partition member will be disengaged from the member 65, as the partition member moves out of the housing. The tank 18, with the burner mechanism thereon, can then be freely inserted into or removed from the housing, preferably by sliding the same along on the angle members 19.

It will be understood that the partition member 70 and the partition member 71 extend for substantially the full length of the housing, and that these members may be provided respectively with flanges 79 and 80 which cooperate with the end walls of the housing. The flanges 79 also tend to stiffen and support the partition mem- 35 ber 70.

At the ends of the housing I provide sealing and guiding means in the form of metal plates 81 which are secured against the inside of the end walls 13 and 14 of the housing at the ends 40 of the lower housing chamber 17. The two plates 81 are of similar form and, as shown in Figs. 1, 5 and 6, these plates are provided with raised or inwardly extending areas 82, 83 and 84. The raised areas 82 are located to be engaged by the end flanges of the partition member 70 so that an air seal will be provided at this point when the hinged front 78 is in closed position. The raised areas 83 engage and close the ends of the air distributor 37 when the tank 45 and burner mechanism are in place, and also engage portions of the ends of the tank to form an air seal at these points. The raised areas 84 engage the ends of the tank and form guides for sliding the tank along the angle members 19. 50

To further facilitate the handling of the tank 18, I may provide the tank with one or more ears or hooks 85 at the front edge thereof, by means of which the tank may be slid along the angle members 19 and withdrawn from the housing. The tank may also be provided with a lifting and carrying bail 86 connected to ears 87 at the ends of the tank.

The tank may also be provided with a suitable filler opening 88 having a removable closure 65 plug or cover 89. I may also provide the tank with a suitable indicating mechanism 90 for visibly indicating the amount of fuel in the tank. If desired, the top wall of the tank may be formed with an upstanding bead 91 which extends 70 around the bushing 32 and forms a retaining means for oil which may escape past the closure member 35. This retaining means prevents any escaping oil from creeping along the outer surface of the tank and resulting in a possible ac- 75

cumulation of combustible liquid or gases beneath the housing.

As will be seen from Fig. 1 of the drawings, the wick and the air distributor 37 project upwardly through the passage 72 so that a flame burning to the front of and above the wick may extend upwardly into the housing above the partition member 70. The heat produced by the flame, and also the combustion gases and heated air, will rise into the upper chamber 25 of the housing. To facilitate the discharge of the heat and the heated air from the housing through the openings 26, and for other reasons also, I construct the housing with the top of the front wall 15 inclined toward the rear wall 16. Such inclination of the front wall allows the rows of openings 26 to be located approximately directly above the burner mechanism so that the air and heat may have a direct and easy exit from the housing.

I also provide the housing with a reflector plate 94, which extends upwardly in the housing above and to the rear of the burner, and which is curved or otherwise shaped so as to cause heat and heated air to be directed toward the front wall 15 and through the openings 26 thereof. This reflector plate may be supported in the housing in any suitable way and may, as shown in this instance, be connected to the housing at or adjacent the top wall 24 thereof and may also be connected to the upwardly extending part 74 of the partition member 71.

As indicated by the arrows 95, some of the heat and heated air rising from the burner will pass substantially directly upwardly and be discharged through the openings 26 and the openings 28. Also, as indicated by the arrows 96, some of the radiant heat will travel forwardly and upwardly from the burner and strike the inclined front wall 15 and be deflected rearwardly against the reflector plate 94 from which the heat will be directed back toward the front wall and outwardly through the openings 26.

If desired, the appearance of the device may be rendered more attractive by providing a row of windows 97 in the front wall 15 at a point where the flame will be visible from outside the housing. In addition to enhancing the appearance of the device the windows also enable one to immediately ascertain whether or not the burner is lighted and operating properly. The hinged section 78 of the front, may if desired, have a latch 98 for releasably holding this section in closed position.

It may be desirable to prevent the rear wall 16 of the housing from becoming overheated so that the device may be placed adjacent a wall or other structure without danger of causing fire or damage, and for this purpose I may provide a row of openings 99 through the partition member 71 so as to permit a flow of air upwardly through the space or passage 100 between the reflector plate 94 and the rear wall 16. Air flowing upwardly through this space may escape through the openings 27 adjacent the top of the housing and such air flow will tend to maintain the rear wall in a relatively cool state.

As mentioned above, the rear wall 16 is inclined toward the front wall and it will be seen that such inclination will prevent the back of the housing from being placed closely against a wall or other structure which might otherwise result in damage or fire. Because of this inclination, it will be seen that even though the rear legs 102 be placed adjacent the wall of a

room, there will always be an air space between the room wall and the rear wall 16 of the housing.

As another feature of my invention I provide novel means for supporting and guiding the air distributor 37, and novel means for adjusting the wick and distributor. The supporting means for the distributor comprises vertical members 103 which slidably extend downwardly into vertical recesses provided at the ends of the wick tube as shown in Figs. 4 and 5. These vertical members 103 extend through notches or openings provided in the forwardly extending part 57 and the Z-like upper part of the front wall 50 of the distributor, and may be provided at their upper end with an enlarged part 104 to which the distributor is connected by suitable fastenings 105. The vertical members 103 slidably telescope into the recesses of the wick tube structure adjacent the end members 40' and, in cooperation with the upwardly extending part 74 of the partition member 71, support and guide the distributor.

The adjusting means for the wick and the air distributor includes a rotary shaft 105' mounted on the closure member 35 so as to extend along within the chamber 40 rearwardly of the wick tube and below the distributor 37. A plurality of star wheels 106, which are adapted to function as gear wheels, are secured to the shaft in spaced relation and have driving cooperation with the wick to cause the same to be raised or lowered as the shaft is rotated. The adjusting means also includes pinions 107 which are secured to the shaft adjacent the ends of the wick tube and which mesh with rack teeth 108 formed on the vertical members 103. The cooperating racks and pinions 107 and 103 cause the air distributor 37 to be positively raised or lowered with the wick as the shaft 105' is rotated but without the weight of the distributor being supported upon the wick.

To render the driving action of the star wheels 106 on the wick more positive and also less destructive to the wick, it may be desirable to reinforce and stiffen the wick such as by applying a correspondingly elongated metal sheet 109 to the rear face thereof. This metal sheet is provided with rows of openings 110 in which the teeth of the star wheels 106 engage.

It will be noted from the drawings, particularly Fig. 4, that the rack teeth 108 extend to the lower end of the members 103 and also that the star wheels 106 are of slightly larger diameter than the pinions 107. When the wick and air distributor are moved upwardly, the larger diameter star wheels will tend to raise the wick a little faster than the pinions raise the distributor. This tends to maintain the upper edge 45 of the wick always firmly pressed against the under side of the flange section 59 of the distributor. Should the upper end of the wick become burned away so as to leave a gap between the upper edge of the wick and the flange section 59, adjustment can be made to close the gap by rotating the shaft to elevate the wick and the distributor sufficiently to cause the lower ends of the racks to overrun and become disengaged from the pinions. When such disengagement occurs it prevents the distributor from being raised higher, but continued rotation of the shaft in the same direction will cause the wick to be elevated and will cause its upper edge 45 to be again pressed against the flange section 59. When the upper edge of the wick has thus been brought into engagement with the flange section 59, the shaft can be rotated in

the reverse direction and the wick and distributor lowered to the proper adjustment.

- Any suitable means may be provided for rotating the shaft 105', and in this instance I show 5 the shaft as having the end 112 thereof projecting through the end member 49' of the wick tube structure and with a knurled knob 114 mounted on the shaft end and drivingly connected thereto with a pin and slot connection 115. 10 The knob normally projects through an opening in the end wall 14 of the heater so that the wick and distributor may be adjusted from the exterior of the heater housing. The pin and slot connection 115 permits the knob to be shifted inwardly through the opening of the housing wall 14 to allow the tank 18 to be withdrawn from the housing. A spring 116 may be provided inwardly of the knob 114 to normally hold the latter in an extended position accessible from the 15 exterior of the housing.

As a further feature of my invention I provide means for controlling the air supply, such that the volume of air flowing to the wick and the burning area will always be substantially proportional to the wick adjustment, and will always be substantially the correct volume of air for efficient burning of the fuel. The proportioning of the air supply in accordance with the wick adjustment may be accomplished in various ways. 20 and means for this purpose may be embodied in the present construction by providing movable shutters 120 and 121, which are arranged to control the flow of air into the elongated space or slot 72 from the lower chamber 17 of the housing. 25 The shutter 120 may be formed on the air distributor 37 as a flange depending from the rear wall 53 of this member. As the air distributor is moved upwardly or downwardly during adjustment of the wick, the shutter 120 will be correspondingly moved to vary the cross-sectional area of the air inlet space between the partition member 71 and the closure structure 35. It will be understood, of course, that the depending flange forming the shutter 120 extends longitudinally 30 of the housing along the lower part of the air distributor 37. When the wick and air distributor are adjusted upwardly to increase the size of the flame and the heat output, the shutter 120 moves away from the closure structure 35 to increase 35 the cross-sectional area of the air inlet space. The increased air inlet opening, thus provided, allows more air to enter the chamber 51 of the distributor to be supplied to the larger flame which will burn from the elevated wick.

The shutter 121 may be an elongated plate arranged for sliding movement adjacent the screen member 65. The shutter formed by this plate covers one or more rows of the openings of the screen member 65 when the shutter is moved upwardly, and uncovers some or all of the openings of the screen member when the shutter is moved downwardly. To operate the shutter proportionately to the adjusting of the wick, I may provide the members 103 with rack teeth 122 on the edges thereof opposite the rack teeth 108, and may provide similar rack teeth 123 on the shutter 121 adjacent the ends thereof. Idler pinions 124 mesh with the rack teeth 122 and also mesh with the rack teeth 123. The idler pinions, as shown in Fig. 5, may be supported on stub shafts 125 mounted in the end members 49' of the wick tube structure.

When the wick and air distributor are adjusted upwardly by rotation of the shaft 105',

the pinion 124 is driven by the rack teeth 122. The direction of rotation of this pinion is such, however, that the rack teeth 123 and the shutter 121 connected thereto are moved in a direction opposite to that of the wick or, in other words, downwardly to uncover some or all of the openings of the screen member 65. When the wick and air distributor are adjusted downwardly, motion is transmitted through the pinion 124 to elevate the shutter 121 to thereby close some of the openings of the screen member 65 and thus reduce the cross-sectional area of the air supply to substantially that required for the setting to which the wick may be adjusted.

The rack teeth 122 are formed over a sufficient portion of the length of the member 103 to afford the desired extent of movement for the shutter 121. By extending these teeth to the extreme lower end of the members 103, it will be seen that these members can be readily disengaged from the pinions after the shutter 121 has been moved to its wide open position. Such disengaging of the rack teeth 122 from the pinions 124 allows the wick and air distributor to be adjusted upwardly as far as desired without limitation by the shutter 121 or its actuating means. When the wick and air distributor are again adjusted downwardly from an abnormally high position, the rack teeth 122 will reengage the pinion 124 and restore the operating connection between the wick adjusting means and the shutter 121.

To provide for lifting or carrying the device whenever this should be desirable, a suitable lifting means, such as the bail or handle 128 may be provided.

From the foregoing description and accompanying drawings it will now be readily understood that I have provided a liquid-fuel burning device of compact and inexpensive construction and adapted to be embodied in a housing of attractive appearance. It will be understood further that with the arrangement of parts provided, my liquid fuel burner is capable of efficient and economical operation on kerosene or other suitable liquid fuel.

While I have illustrated and described the liquid-fuel burning device of my invention in a somewhat detailed manner, it will be understood, of course, that I do not wish to be limited to the precise details of construction and arrangements of parts illustrated and described, but regard the invention as including such changes and modifications as do not involve a departure from the spirit of the invention and the scope of the appended claims.

Having thus described my invention, I claim:

1. In a liquid-fuel burner the combination of a tank having a wick tube structure thereon, a wick in said tube structure and adapted to have a portion project therefrom, means providing an air passage adjacent said wick tube structure, an air distributor disposed in said air passage and having a part thereof engageable with the wick, said distributor being movable in said passage and having a rack slidably on the wick tube structure, and means operable to cause movement of the wick and distributor comprising a rotary actuating shaft having a star wheel engaging the wick and a pinion meshing with the rack, said star wheel being of greater diameter than the pinion whereby the rate of feed of the wick exceeds the rate of movement of the distributor to insure engagement of the wick with the distributor.

2. In a burner structure, a housing having air inlet openings adjacent the bottom thereof, a fuel tank in the housing having a wick tube extending upwardly therefrom, a wick in said tube and normally projecting therefrom, said housing having an outwardly movable front and air deflecting members in said housing extending into adjacently spaced relation to provide an air passage into which said wick projects, one of 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255
